UNITED STATES PATENT OFFICE.

HENRY L. SMITH, OF WATERBURY, CONNECTICUT, ASSIGNOR TO THE E. J. MANVILLE MACHINE COMPANY, OF WATERBURY, CONNECTICUT, A CORPORATION OF CONNECTICUT.

HEADING-MACHINE.

1,244,912.

Specification of Letters Patent. Patented Oct. 30, 1917.

Application filed September 14, 1916. Serial No. 120,028.

To all whom it may concern:

Be it known that I, HENRY L. SMITH, a citizen of the United States, residing at Waterbury, in the county of New Haven and 5 State of Connecticut, have invented a new and useful Improvement in Heading-Machines, of which the following is a specification.

This invention relates to the type of machine for swaging the ends of wire rod into which machine a continuous piece of stock is fed and the exact length cut off and carried over into line with the heading punch and die.

10 The object of this invention is to provide for a machine of this character a stock cut-off mechanism which is very powerful, durable and quick in action so that heavy stock will be cut cleanly and squarely.

15 In attaining this end a barrel cam, connected with a gear that is driven by a pinion on the crank-shaft, is arranged to oscillate a rocker arm on a shaft which has a rocker lever, one end of which engages a 20 shoe carried by the reciprocating knife holder, and the other end of which is engaged by a spring plunger, the cam groove being cut in such manner that it causes the knife to act on the stock with a quick and 25 powerful blow until the piece is sheared off and then allows the spring to continue the movement of the knife and carry the cut off piece over into line with the punch and die.

30 The invention is particularly applicable to what is known as single or multiple stroke solid-die headers, that is, those headers which have a solid die and a punch or punches which act either once or more than once on each piece of stock that is cut off 35 and presented to the die.

35 Figure 1 of the accompanying drawings shows a plan view of a well known double stroke solid die heading machine provided with a quick cut-off which is constructed according to this invention. Fig. 2 shows on a larger scale a plan of the cut-off mechanism. Fig. 3 shows a side elevation of the cut-off mechanism. Fig. 4 is a view looking from the rear toward the cut-off mechanism. Fig. 5 is a side view of the cut-off rocker shaft and its cam arm and knife-slide operating lever. Fig. 6 is a view of the cut-off disassociated from the rest of the machine. Fig. 7 is a view showing the

relative positions of the feed quill, stock, 55 knife, die and punch at the time the cutter is shearing off a piece of stock.

The machine illustrated has a reciprocating gate 1 that is connected by a crank rod 2 with a crank 3 on the shaft 4 which is 60 provided with the fly wheel 5. In the front end of the horizontally movable gate is the vertically movable slide 6 which carries the punch holder 7 with the punch 8. The die 9 is secured in the die block 10 mounted in 65 the end of the frame 11 in line with the punch. The stock is fed at the proper time through the quill 12 by the feed mechanism 13. As these features of the machine are 70 old and well known they are not further described in detail.

In these machines after the stock has been fed and while the punch is returning from its stroke, the knife is advanced for cutting off the proper length of stock and carrying 75 it into line with the punch and die. As the stock is quite heavy, for instance, it may be rod a half inch in diameter, considerable force is required to shear it. In the prior machines that are powerful enough to sever 80 such stock, the knife moves with a relatively slow motion and this tends to bend the stock and stretch the metal, leaving uneven and untrue or angular ends. With the improved cutting mechanism, which forms the subject 85 of this invention, the knife is moved not only very powerfully, but very quickly so that it strikes the stock with a heavy blow and severs it without bending it, making a 90 clean shear and leaving square ends.

95 This is accomplished by connecting a barrel cam 14 with a heavy gear 15 that is mounted on the frame so as to be engaged with and driven by a pinion 16 on the crank-shaft. Running in the cam groove 17 of the barrel cam is a roller 18 on the end of a rocker arm 19 formed at one end of a shaft 20 that is mounted in bearings 21 which are secured to the side of the frame. Formed at the other end of this rocker shaft is a 100 lever 22. In practice the rocker shaft, rocker arm and rocker lever have been made of a single heavy steel casting.

105 The upper end of the rocker lever is rounded and engages a shoe 23 located in a mortise in the end of a slide 24 which is movable horizontally back and forth through the side of the machine frame. On

the inner end of this slide is the knife 25, and carried by the slide and projecting over the cutting edge of the knife are spring fingers 26 which are designed to grasp the stock 5 as it is being cut and hold the cut off piece while it is being carried from cutting position into line with the punch and die. The cam groove in the barrel cam which oscillates the rocker arm is so cut that as the section 27 engages the roll on the rocker arm the parts are operated to drive the knife inward very quickly and powerfully with a positive movement, and following this the wall of the cam groove on one side is cut 10 away so that after the stock is severed the roll for a time is free from the control of the cam. Engaging with the lower end of the lever on the rocker shaft is a plunger 28 which is thrust outwardly by a heavy 15 spring 29, these parts being arranged in a socket in the frame which supports the cutting mechanism. After the cam has moved the parts so as to sever the stock and the roll reaches the cut away portion of the cam 20 groove, the spring plunger thrusting against the lower end of the lever swings the lever and causes it to push the knife and stock holding fingers farther inward and carry the stock which has been severed from cutting 25 position into line with the punch and die. The knife is preferably started a little away from the stock so that it has the momentum of full speed when it strikes the stock for cutting it off, and thus it gives a quick, 30 powerful, positive blow and not a bending or crushing push, and cuts the stock off 35 squarely.

In some machines it has been found advisable to attach a supporting plate 30 to 40 the punch holder for backing up the inner end of the stock as it is being cut. The end of this supporting plate is beveled (as shown in Fig. 7) so that as the knife moves in and carries the stock over and the punch and punch 45 holder recede, the end of the piece of stock which is being cut will slide down the beveled end of the supporting plate, and the axis of the cut piece will keep parallel with the axis of the punch and die, that is, the angle on the 50 end of the supporting plate is made proportionately to the inward movement of the knife and the backward movement of the punch.

With this mechanism the barrel cam is 55 driven very powerfully and its cam groove is so cut that it gives a quick, powerful, positive stroke of the knife for severing the stock. The rocker shaft with its arm and lever are strong and durable and they operate 60 quickly and powerfully with a minimum amount of friction and wear. The knife acts in a straight line, and as stated with a powerful blow so that it will sever heavy stock squarely and truly without bend. 65 The spring plunger then causes the knife to

carry the severed piece of stock into line with the punch and die, and should any part become mistimed or displaced, for instance, if a die should pull out so as to obstruct the stock, the spring yields and no damage will 70 be done.

The invention claimed is:

1. A cut off for a heading machine comprising a pinion on the crank-shaft, a gear engaged and driven by said pinion, a barrel 75 cam connected with the gear, a rocker arm adapted to be oscillated by said cam in a plane longitudinal with relation to the axis of the cam, a shaft extending at right angles to the crank-shaft and adapted to be rotarily 80 oscillated by said rocker arm, a lever on said rocker shaft, a slide adapted to be reciprocated parallel with the crank-shaft by the lever, and a knife mounted on said slide.

2. A cut-off for a heading machine comprising a pinion on the crank-shaft, a gear engaged and driven by said pinion, a barrel cam connected with said gear, a rocker arm adapted to be oscillated by the cam, a shaft adapted to be turned by said rocker arm, a lever on said shaft, a slide adapted to be reciprocated by the upper end of the lever, a knife mounted on said slide, and a spring plunger thrusting against the lower end of the lever, the cam groove being cut so that 95 the knife slide is first pushed in positively by the cam and then its movement is completed by the thrust of the spring plunger.

3. A cut off for a heading machine comprising a pinion on the crank-shaft, a gear engaged and driven by said pinion, a barrel cam connected with the gear, a rocker arm adapted to be oscillated by said cam in a plane longitudinal with relation to the axis of the cam, a shaft extending at right angles 100 to the crank-shaft and adapted to be rotarily oscillated by said rocker arm, a lever on said rocker shaft, a slide adapted to be reciprocated parallel with the crank-shaft by the lever, a knife mounted on said slide, 105 and spring holding fingers attached to the slide and having bent ends that project toward each other over the front edge of the knife.

4. A cut-off for a heading machine having 115 a gear driven barrel cam, a rocker arm oscillated by said cam, a shaft turned by the rocker arm, a lever on the rocker shaft, a spring plunger thrusting against the lower end of the lever, a shoe carried by the upper 120 end of the lever, a slide engaged by said shoe, and a knife mounted on the slide.

5. A cut off for a heading machine comprising a gear driven barrel cam, a shaft at right angles to the axis of said cam, a 125 rocker arm attached to one end of said shaft and engaging said cam, a lever attached to the other end of said shaft, a shoe fitting the upper end of the lever, a slide with a recess containing the shoe, a knife attached 130

to the slide, and spring fingers attached to the slide and projecting over the cutting edge of the knife.

6. A cut-off for a heading machine having a gear driven barrel cam, a rocker arm oscillated by said cam, a shaft turned by said arm, a lever on said rocker shaft, a spring plunger thrusting against one end of said lever, a slide engaged by the other 10 end of the lever, and a knife carried by the slide.

7. In combination with the crank-shaft

and reciprocating punch holder of a heading machine, of a barrel cam driven from the crank-shaft, a rocker arm oscillated by 15 the cam, a shaft turned by the rocker arm, a lever on the rocker shaft, a slide reciprocated by the lever, a knife carried by the slide, stock holding fingers carried by the slide, and a backing plate mounted on the 20 punch holder for supporting the end of the stock while being cut by said knife and held by said fingers.

HENRY L. SMITH.
